UNITED STATES PATENT OFFICE.

JACOB GESSERT, OF BUFFALO, NEW YORK.

BIT-BRACE.

No. 812,198.

Specification of Letters Patent.

Patented Feb. 13, 1906.

Application filed August 27, 1904. Serial No. 222,426.

To all whom it may concern:

Be it known that I, JACOB GESSERT, a citizen of the United States, residing at Buffalo, in the county of Erie and State of New York, 5 have invented certain new and useful Improvements in Bit-Braces, of which the following is a specification.

This invention relates to improvements in bit-braces; and its primary object is to provide a brace which can be used in very small quarters, such as are inaccessible to ordinary braces, it being particularly designed for cabinet-work, which often requires boring to be done in pigeonholes of desks and other similar places ordinarily inaccessible to a bit-brace.

Other objects are to provide a bit-brace wherein the actuation of the same is caused by a pull and thrust action on the operating-lever or handle; by means of which action the head of the brace carrying the bit can be inserted into a small space and the handle actuated from without such space; to so construct the brace that it may be actuated by an oscillating movement of the handle; to provide a pressure device independent of the handle, which permits the head of the brace to be inserted into a small space and whereby sufficient pressure may be exerted on the head to cause the bit to bite or take hold; to provide braking means whereby the chuck or stock is held against retrograde movement during the initial action of the brace, or, in other words, until the bit enters the wood sufficiently to cause enough friction to prevent retrograde movement of the bit, and to otherwise improve bit-braces.

To these ends the invention consists in the construction, arrangement, and combination 40 of parts to be hereinafter described, and particularly pointed out in the appended claims.

In the drawings, Figure 1 is a perspective view of my improved bit-brace, the handle being shown for operation by a thrust and pull action. Fig. 2 is a top plan view of the same, the handle thereof being shown as used when swinging or oscillating through an arc of a circle. Fig. 3 is a longitudinal section, on an enlarged scale, taken on line 3 3, Fig. 2. Fig. 4 is a transverse section through the head of the handle and the stock, taken on line 4 4, Fig. 3. Fig. 5 is a horizontal section through the pressure-bar head and the shank of the stock, taken on line 5 5, Fig. 4. Fig. 6 is a horizontal section taken on line 6 6, Fig. 3. Fig. 7 is a longitudinal section taken on line

7 7, Fig. 2. Fig. 8 is a horizontal section taken on line 8 8, Fig. 7. Fig. 9 is an enlarged detached perspective view of one of the cam-disks whereby the actuating-pawl are disengaged from the ratchet.

Referring to the drawings in detail, like letters of reference refer to like parts in the several figures.

The handle comprises a radial bifurcated 65 head A and a pivoted holding portion C. The bifurcated head has its outer end closed by a wall, as at a, and is provided with a cylindrical shank B, having its outer end flattened on one side to form substantially a semicylindrical extension b. The holding portion C of the handle is preferably cylindrical with a portion of its length of corresponding diameter to the shank B. The inner end of said holding portion is pivotally attached to said 70 shank and provided with a complementary flattened extremity through which and the flattened end of the shank a pivot-pin c is passed, thus permitting the holding portion of the handle to be swung at an angle to said 75 shank for operating the brace by a thrust-and-pull action. A sleeve D surrounds the handle and is movable longitudinally thereon, its function being to lock the holding portion of the handle rigidly to the head A when swung 80 in line therewith, so as to allow the operation of the brace by a swinging movement of the handle through an arc of a circle. At such times the sleeve is moved against the head to completely surround the shank and the complementary flattened portions of the same 85 and the handle.

Within the bifurcated head A is located a ratchet-wheel E, and passing through the latter and registering openings in the arms of the 95 said head is the shank f of a stock or chuck F. Said ratchet-wheel is secured to said shank by a pin f' to cause the latter to revolve therewith. The stock may be of any desired type; but for the perfect and free working of other 100 parts to be hereinafter described the same is preferably cylindrical.

Located between the two arms of the bifurcated head in the intervening space separating the ratchet-wheel E from the rear wall 105 a of said head are two ratchet-pawls G, pivotally attached by pivot-pins g, passing therethrough between the ends thereof and through the arms of the head. Each pawl has a socket or depression g' formed in its opposing face on that side of the pivot-pin near the rear wall 110 of the head, and interposed between the pawls

with the ends thereof seated in said sockets is an expansion-spring H, serving to separate the free ends of the pawls, and consequently force the acting ends thereof into engagement 5 with the ratchet-wheel.

Owing to the arrangement of the various parts, the brace would be rendered undesirable by the engagement of both pawls with the ratchet, it being constructed, primarily, 10 as a ratchet-brace. I therefore provide means for disengaging either one of said pawls from the ratchet, which comprises two cam-disks I, located at opposite ends of the rear wall of the ratchet-head and revolvably secured thereto by a pivot-pin J, passing through said wall. Acting cam-faces K are formed by gradually diminishing the thickness of each disk from a point k to a point k', thus forming inclined cam-faces around central bosses k². The cam-face of each disk 20 lies in operative proximity to the inner ends of the pawls G, and upon revolving said disks the gradually-inclined surfaces cause the pawls to be disengaged from the ratchet. 25 The said disks are loosely mounted on the pivot-pin J for independent rotation.

It is apparent from the foregoing that the brace may be operated by an oscillating movement of the handle through an arc of a 30 circle, which is desirable in open places where space will permit of such movement, as increased leverage can be obtained, or by a pull-and-thrust movement of the handle when only the short shank of the head is moved through 35 an arc of a circle.

As it is always necessary that pressure be exerted on the bit, I provide a pressure-bar L, which is advisedly positioned in line with the chuck or stock for a purpose to appear 40 hereinafter, it having at its inner end an upwardly and inwardly extending arm l, which terminates in a head l', having a depression or socket l², opening inward, into which latter the upper end of the stock-shank fits. The 45 latter is provided with a circumferential groove M, into which flat keys m fit, which pass through lateral openings m' in the head of the pressure-bar and whose inner ends are curved to correspond to the reduced portion 50 of the shank formed by said groove. To prevent accidental displacement of said keys from the groove in the shank, suitable screws N are screwed into openings n in the head of the pressure-bar and pass through perforations n' in said keys. By this arrangement 55 the pressure-bar is locked securely to the chuck and is free to turn on the shank thereof, while allowing the chuck to turn without turning said head. The pressure-bar is made 60 hollow and is open at its outer end and provided with slots O at diametral points. A stop-bushing P is secured in said bar near its outer end by a pin p, passing through the same and entering said bushing. The latter 65 is provided with a longitudinal opening p',

through which and a perforation p² in the inner closed end of the bar a brake-rod R is passed, which extends from opposite ends of said rod. The inner end of said brake-rod has affixed thereon a brake-shoe R', adapted 70 for engagement with the stock or chuck, while the outer end of said rod is threaded to receive an adjusting-nut S, which partly enters the open end of the pressure-bar. A pin T is passed through the brake-rod and has its ends 75 extending into the slots O in said pressure-bar, which prevents turning of the brake-rod, while serving as a convenient guide. Surrounding said brake-rod with its ends bearing against the pin T and the inner end of the 80 stop-bushing P is a spiral spring U, which serves to hold the brake-shoe with the necessary pressure against the chuck or stock of the brace.

In operating the device the adjusting-nut S 85 is turned to allow the spring U to force the brake-shoe against the chuck. The sleeve D is then moved along the handle to permit the same to be swung at a right angle or at any other angle to the shank of the head A, or if 90 at an angle to said shank and it is desired to use the same in rigid form the handle is swung in line with said shank and the sleeve moved inward along the handle to surround both the said shank and the inner end of the 95 handle. The pressure-bar is then taken hold of and the tool placed against the work. The handle is actuated in either manner described as may be necessary or desirable, and after 100 the bit has entered the work and is held sufficiently by friction to prevent retrograde movement the adjusting-nut is screwed farther onto the brake-rod, which causes the brake-shoe to be drawn away from the stock or chuck. After the desired depth is bored 105 the cam-disks are both revolved to disengage the acting pawl from the ratchet-wheel and engage the idle pawl therewith, which causes a reversal and the withdrawal of the bit. It is therefore apparent that the brake-shoe is 110 put into service only when starting to bore, and as soon as reverse movement of the bit is unlikely it is withdrawn from the chuck. This is a very essential feature when the 115 brace is used in small quarters, which requires pressure to be exerted on the brace from without such quarters.

While the construction shown and described is the preferred one, I do not wish to limit myself to such construction, as many 120 changes may be resorted to without departing from the scope of my invention or sacrificing any of the advantages thereof.

Having thus described my invention, what I claim is—

1. A bit-brace comprising in combination, 125 a pressure-bar and a stock mounted to rotate therein and be governed thereby, said stock having a ratchet-wheel rigid therewith, a handle having a head rotatable on said stock 130

- and carrying a pawl engaging said ratchet-wheel, and a braking device carried by said pressure-bar engaging said stock and resisting rotation on the return of the pawl.
- 5 2. A bit-brace comprising in combination, a hollow pressure-bar having an offset arm, a stock mounted to rotate in said arm and having a ratchet-wheel rigid thereon, a handle rotatable on said stock and carrying a pawl 10 engaging said ratchet-wheel, and a braking device comprising a brake-shoe and a rod mounted in said pressure-bar.
- 15 3. A bit-brace comprising in combination, a hollow pressure-bar having an offset arm, a stock mounted to rotate in said arm and having a ratchet-wheel rigid thereon, a handle rotatable on said stock and carrying a pawl 20 engaging said ratchet-wheel, and a braking device comprising a brake-shoe, a rod carrying said brake-shoe mounted in the pressure-bar, a spring tending to force said rod inward to hold said brake-shoe against the stock, and means for drawing said rod outward against the action of said spring.
- 25 4. A bit-brace comprising in combination, a hollow pressure-bar having an offset arm and longitudinal slots at diametrically opposite points, a stock mounted to rotate in said offset arm and having a ratchet-wheel rigid 30 thereon, a handle rotatable on said stock and carrying a pawl engaging said ratchet-wheel, and a braking device comprising a rod mount-

ed in said pressure-bar and having its ends projecting therefrom and its outer end threaded, a brake-shoe at the inner end of said rod, 35 an adjusting-nut fitting onto the threaded end of said rod, a pin passing through said rod and guided in the slots in the pressure-bar, a stop-bushing held in said pressure-bar, and spiral springs surrounding said bar and 40 bearing with its ends against said pin and bushing, respectively.

5. A bit-brace comprising in combination, a pressure-bar and a stock mounted to rotate therein and be governed thereby, said stock 45 having a ratchet-wheel rigid therewith, an operating-handle carrying a pawl engaging said ratchet-wheel and having a head rotatable on said stock provided with a radial shank, and a holding portion pivoted to said 50 shank and capable of being swung at an angle to or in line with said shank, means for locking the handle and shank rigid when alined, and a braking device carried by said pressure-bar engaging said stock and resist- 55 ing rotation on the return of the pawl.

In testimony whereof I have affixed my signature in the presence of two subscribing witnesses.

JACOB GESSERT.
